UNITED STATES PATENT OFFICE.

WILLIAM M. CHACE, OF DETROIT, MICHIGAN.

DETACHABLE CONE FOR LAUNDRY EXTRACTORS.

Application filed August 22, 1921. Serial No. 494,099.

To all whom it may concern:

Be it known that I, WILLIAM M. CHACE, a citizen of the United States, residing at Detroit, county of Wayne, State of Michigan, have invented a certain new and useful Improvement in Detachable Cones for Laundry Extractors, and declare the following to be a full, clear, and exact description of the same, such as will enable others skilled in the art to which it pertains to make and use the same, reference being had to the accompanying drawings, which form a part of this specification.

This invention relates to detachable cones for laundry extractors and the object of the invention is to provide a cone for attachment to a laundry extractor to prevent tearing of the clothes while the water is being extracted therefrom. This invention is adapted for use in a laundry extractor comprising an outer cylindrical case in which a cylindrical apertured metal basket is rotatably mounted, the clothes being placed in the basket and the basket being rotated at a high rate of speed to extract the water from the clothes by centrifugal force, the water being thrown outwardly into the casing during rotation of the basket. The chief difficulty with this type of extractor is that when the basket is loaded with wet clothes by inexperienced persons or one who is not expert in operating an extractor, some of the clothes are placed too near the center or extend across the center and when the basket is so loaded and revolved at the extremely high rate of speed which is customary with extractors of this type the clothes extending across or near the center are torn due to the centrifugal force applied by rotation of the basket and for this reason laundries are put to considerable expense in replacing the clothes so torn. Therefore one of the principal objects of this invention is to provide a device for preventing the tearing of clothes in this manner. Another difficulty in this type of extractor is that should the basket be loaded unevenly with more clothes in one side than in the other the basket tends to become eccentric in action when revolving at a high rate of speed, thus quickly wearing

the bearings and putting considerable strain on all parts of the machine. Another object of the invention is to provide a cone extending upwardly in the center of the basket which spaces the clothes from the center of the basket on all sides so that the basket can be loaded much more evenly and with greater speed and ease than heretofore. A further object of the invention is to provide a cone of the character described which is light in weight and which may solidly be secured in position in the center of the basket. These objects and the several novel features of the invention in its preferred form are hereinafter more fully described and claimed and the preferred form of construction by which these objects are attained is shown in the accompanying drawings in which—

Fig. 1 is a section through an extractor showing the means for securing the cone in place.

Fig. 2 is an enlarged section through the cone showing the inner parts in elevation.

As shown in Fig. 2 a shell 1 is provided in the shape of a truncated cone which is preferably spun from copper and plated. The cone is closed at the top with a bell shaped end and is provided with an aperture for receiving the upper end of a rod 2. The rod 2 is threaded at the upper end and nut 3 is threaded thereon, a washer 4 being positioned on the nut 3 about the rod 2 as shown. This washer 4 supports a bell shaped metal disc 5 which conforms to the shape of the upper end of the conical shell 1. As will be noted from Fig. 2 the bell shaped disc 5 is positioned within and supports the upper end of the cone centrally on the rod 2, the rod 2 extending through an aperture provided in the cone. A washer 6 is positioned over the rod 2 on the exterior of the cone and a nut 7 is threaded on the upper end of the rod 2 so that the parts are bindingly secured between the nuts 3 and 7. At the lower end the rod 2 is threaded into a nut 6 and the nut 6 is provided with an enlarged threaded aperture 7 adapted to be threaded onto the threaded end 8 of a shaft 9 as shown in Fig. 1. The nut 6 is provided with a flange 10 at

the lower end which when threaded onto the end 8 of the shaft 9 engages the bottom of the basket or perforated receptacle 11. This basket 11 is provided with a series of apertures 12 and is keyed to the shaft 9 by a key 13 and as shown in Fig. 1 the shaft 9 is provided with a shoulder 14 on which the portion 15 of the basket 11 seats, the enlarged portion of the shaft being rotatably mounted in the casing 16. To secure the cone in place the usual nut is removed from the threaded end 8 of the shaft 9 and the nut 6 is threaded thereon so that the flange 10 thereof binds the portion 15 of the basket between the shoulder 14 of the shaft and the said flange 10, the key 13 preventing rotation of the shaft in relation to the basket. At this time the rod or shaft 2 is threaded into the upper end of the nut 6 and the lock nut 17 is threaded down tightly against the upper end of the nut 6 to lock the rod from movement in relation to the nut 6. At this time the nut 3 is threaded on to the upper end of the shaft 2 and the washer 4 and bell shaped disc 5 are positioned thereon. The conical shell 1 is then placed over the end of the shaft 2 on the disc 5 so that the flange 18 at the bottom of the cone engages the bottom of the basket. Should the flange not engage the bottom of the basket properly the cone is removed and the nut 3 is adjusted so as to allow the proper engagement at which time the washer 6' is positioned over the end of the shaft and the nut 7 is turned down tightly to lock the parts in position at the upper end of the shaft between the nuts 3 and 7.

When this has been done the basket may be loaded with wet clothes, the cone 1 assisting in spacing the clothes from the center of the basket and in loading the basket evenly so that it is not out of balance. The cone 1 also prevents any of the clothes being positioned diametrically across the center of the basket and, when the basket is rotated at a high rate of speed by rotation of the shaft 9 the clothes due to the centrifugal force applied gather against the vertical wall of the basket at which time the water within the clothes due to the centrifugal force is expelled from the clothes through the apertures 12 in the sides of the basket. In some extractors the shaft 9 is flush with the bottom of the basket in which case a recess is drilled in the end of the shaft and threaded to receive the threaded lower end of the rod 2 which is locked in the recess by the lock nut 17. The basket may also be secured to the shaft 9 by a pin or other means beside the key 13.

In making the first cones for this purpose a true conical shell was utilized and the nut 3 and bell shaped disc 5 were not used, but a nut similar to the nut 7 was utilized

to force the lower edge of the shell into engagement with the bottom of the basket. To secure the shell solidly in place the nut 7 was turned down tightly which would draw the cone out of shape at the upper end and very often cause the same to break. From that construction the cone having the bell shaped upper end was devised and the nut 3 and bell shaped disc were utilized so that the cone could be bindingly secured in place at the upper end and would not break when bindingly secured in place. It will be thus seen from the construction of the cone that no clothes can be positioned in the center of the basket, thus preventing the same from being torn while the water is being extracted therefrom.

From the foregoing description it becomes evident that the device is very simple and efficient in operation, will not easily get out of order, is very strong, may be rigidly secured in position, is of low manufacturing cost and provides a device which accomplishes the objects described.

Having thus fully described my invention its utility and mode of operation what I claim and desire to secure by Letters Patent of the United States is—

1. A detachable cone for use with a centrifugal extractor comprising the combination with a perforated basket having a shaft secured centrally thereto and provided with a threaded end extending into the basket, of a nut threaded onto the threaded end of the shaft and having a threaded recess in the upper end, a rod threaded into the said recess, the said rod supporting a bell shaped disc at the upper end, a conical shell having a flange at the lower edge adapted to engage the bottom of the basket, said shell fitting over the bell shaped disc at the upper end and a nut threaded on the upper end of the said rod and adapted when turned up to bindingly secure the cone and the bell shaped disc together.

2. A detachable cone for use with a centrifugal extractor comprising the combination with a perforated basket having a rotatable shaft keyed thereto and provided with a threaded end extending into the basket, of a nut threaded onto the threaded end of the shaft and having a flange adapted to engage the bottom of the basket, a rod secured to the said nut, a bell shaped disc carried by the upper end of the said rod, a conical shell fitting over the said disc and having a flange adapted to engage the bottom of the basket, the disc fitting the upper end of the shell and a nut on the upper end of the rod binding the shell in position.

3. A detachable cone for use with a centrifugal extractor comprising the combination with a perforated basket having a ro-

tatable shaft keyed thereto and provided with a threaded end extending into the basket, of a nut threaded onto the threaded end of the shaft and having a flange adapted to engage the bottom of the basket, a rod secured to the said nut, a bell shaped disc carried by the upper end of the said rod, a conical shell fitting over the said disc and having a flange adapted to engage the

bottom of the basket, the disc fitting the upper end of the shell, a nut on the upper end of the rod binding the shell in position and means for adjusting the position of the disc longitudinally of the rod.

In testimony whereof, I sign this specification.

WILLIAM M. CHACE.
